(57) **CLAIM**

The ornamental design for the gaming machine display including an outer symbol display having a display window and an inner symbol display, as shown and described.

DESCRIPTION

FIG. 1 is a front perspective view of the gaming machine display including an outer symbol display having a display

window and an inner symbol display of my new design, that portion of the gaming machine shown in phantom is not part of the design sought to be patented and is provided for environmental purposes only;

FIG. 2 is a front view of the gaming machine display of my new design illustrated in FIG. 1, that portion of the gaming machine shown in phantom is not part of the design sought to be patented and is provided for environmental purposes only;

FIG. 3 is a left side view of the gaming machine display of my new design illustrated in FIG. 1, that portion of the gaming machine shown in phantom is not part of the design sought to be patented and is provided for environmental purposes only, and wherein the right side is a mirror image thereof;

FIG. 4 is a top plan view of the gaming machine display of my new design illustrated in FIG. 1, that portion of the gaming machine shown in phantom is not part of the design sought to be patented and is provided for environmental purposes only;

FIG. 5 is a front view of an alternative embodiment of the gaming machine display including an outer symbol display having a display window and an inner symbol display of my new design, that portion of the gaming machine shown in phantom is not part of the design sought to be patented and is provided for environmental purposes only;

FIG. 6 is a front view of a further alternative embodiment of the gaming machine display including an outer symbol display having a display window and an inner symbol display of my new design, that portion of the gaming machine shown in phantom is not part of the design sought to be patented and is provided for environmental purposes only;

FIG. 7 is a front perspective view of a further alternative embodiment of the gaming machine display including an outer symbol display having a display window and an inner symbol display of my new design, that portion of the gaming machine shown in phantom is not part of the design sought to be patented and is provided for environmental purposes only;

FIG. 8 is a front view of the gaming machine display of the alternative embodiment of my new design illustrated in FIG. 7, that portion of the gaming machine shown in phantom is not part of the design sought to be patented and is provided for environmental purposes only;

FIG. 9 is a left side view of the gaming machine display of the alternative embodiment of my new design illustrated in FIG. 7, that portion of the gaming machine shown in phantom is not part of the design sought to be patented and is provided for environmental purposes only, and wherein the right side is a mirror image thereof;

FIG. 10 is a top plan view of the gaming machine display of the alternative embodiment of my new design illustrated in FIG. 7, that portion of the gaming machine shown in phantom is not part of the design sought to be patented and is provided for environmental purposes only;

FIG. 11 is a front view of a further alternative embodiment of the gaming machine display including an outer symbol display having a display window and an inner symbol display symbol of my new design, that portion of the gaming machine shown in phantom is not part of the design sought to be patented and is provided for environmental purposes only; and,

FIG. 12 is a front view of a further alternative embodiment of the gaming machine display including an outer symbol display having a display window and an inner symbol display symbol of my new design, that portion of the gaming machine shown in phantom is not part of the design sought to be patented and is provided for environmental purposes only.
